(57) CLAIM

The ornamental design for sport wear, as shown and described.

DESCRIPTION

FIG. 1 is a back elevational view of the sport wear in one of intended use positions and showing the outer surface of the sport wear.

FIG. 2 is a front elevational view of the sport wear of FIG. 1;

FIG. 3 is a right plan view thereof;

FIG. 4 is a left plan view thereof;

FIG. 5 is a top plan view thereof;

FIG. 6 is a bottom plan view thereof;

FIG. 7 is a back elevational view of the sport wear in an inside-out configuration inside surface; and,

FIG. 8 is the left plan view of FIG. 7.

The broken lines in the drawing views illustrate portions of the sport wear that form no part of the claimed design.
